UNITED STATES PATENT OFFICE.

HARRY R. NORTHUP AND CHARLES L. SNYDER, OF DES MOINES, IOWA.

HUMIDOR CIGAR HOLDER.

Application filed April 7, 1926. Serial No. 100,359.

The object of our invention is to provide a humidor cigar holder of simple, durable and inexpensive construction.

A further object is to provide such a 5 humidor adapted to receive a moisture containing absorbent element and having means for holding cigars away from direct contact with the moisture absorbent element.

With these and other objects in view, our 10 invention consists in the construction, arrangement and combination of the various parts of our humidor cigar holder, whereby the objects contemplated are attained, as hereinafter more fully set forth, pointed out 15 in our claim, and illustrated in the accompanying drawings, in which:

Figure 1 is a side elevation of a humidor embodying our invention, parts being broken away and parts being shown in vertical sec- 20 tion.

Figure 2 is a detail, sectional view taken on the line 2—2 of Figure 1; and

Figure 3 is a detail, sectional view taken on the line 3—3 of Figure 1, looking in the 25 direction indicated by the arrows on the section line.

In the accompanying drawings, we have used the reference numeral 10 to indicate generally the casing, which has a bottom, 30 side and end members and is about of the proper size to contain a row of cigars, and to permit cigars of the ordinary length to project from its top. The bottom is in the form of a rounded channel 10^a, as shown.

Around the top of the casing 10 is a bead 35 or rib 10^b for reinforcing purposes.

We provide a top or the like 11, comprising a downwardly opening casing member of similar width and thickness, but of con- 40 siderably less height.

The upper part of the top 11 is intended to receive a strip or layer or body of moisture absorbent material 12.

Received in the lower part of the top 11 45 and fitted therewithin is a casing member 13, the lower part of which projects substantially below the lower edge of the top 11. The upper part of the casing member 13 has the top end or the like 13^a, provided with a

central, longitudinal, downwardly project- 50 ing rib 14, and having on opposite sides of said rib, the rows of holes 15 for the escape of vapor or moisture.

The casing member 13 fits by frictional engagement into the top 11. The lower 55 part of the casing portion 13 can be slid into the upper part of the casing 10 and will engage the same frictionally.

Thus for short cigars, the casing 13 is ad- 60 justed downwardly in the top 11, so that a greater portion of it projects into the cas- 65 ing 10, so that when the parts are fitted to- 70 gether, there will be but little play of the cigars up and down.

The rib 14 engages the adjacent ends of 65 the cigars and prevents the cigars from standing too close to the holes 15 and thus 75 getting too damp.

In Figure 2, we have shown cigars 16 in 70 the humidor holder.

Changes may be made in the details of the 75 structure and arrangement of the parts of our improved device and in the materials from which the humidor cigar holder is made without departing from the real spirit 80 and purpose of our invention, and it is our intention to cover by our claim, any modified forms of structure or use of mechanical equivalents, which may be reasonably in- 85 cluded within its scope.

We claim as our invention:

In a device of the class described, a lower 90 casing member open at its upper end, a top casing member open at its lower end, mois- 95 ture absorbent material at the top part of said top member, and an intermediate mem- 100 ber frictionally received in the lower part of the top member and projected therefrom and adapted to be partially, frictionally received in the upper part of the said lower member, and having in its upper end a plurality of openings, and downwardly projecting means for engaging cigars and holding them away from said openings.

Des Moines, Iowa, March 22, 1926.

HARRY R. NORTHUP.
